UNITED STATES PATENT OFFICE.

ALFRED W. BRUCE, OF NEW YORK, N. Y.

LOCOMOTIVE FRAME.

Application filed February 15, 1928. Serial No. 254,368.

This invention relates to the frames or bed members, applied in the construction of locomotive engines, for supporting the boiler and running gear upon the axles thereof, and acting as the means of transmission of the tractive effort exerted by the action of the pressure of steam upon the pistons of the engines, from said pistons to the draw bars of the locomotives.

10 The invention is of the same general character as that set forth in Letters Patent of the United States No. 1,645,687, granted and issued to the applicant, Alfred W. Bruce, under date of October 18, 1927, and its object 15 is to provide a fabricated structure of such type which shall attain all the advantages of that disclosed in said Letters Patent, with a more effective disposition of the connecting members.

20 The improvement claimed is hereinafter fully set forth.

In the accompanying drawing: Figure 1 is an isometrical view of a locomotive frame, illustrating an embodiment of the invention; 25 Fig. 2, a partial plan or top view; Fig. 3, a view, the right hand half of which is a vertical longitudinal section, on the line *a a* of Fig. 2, and the left hand half, a partial side elevation; Fig. 4, a view, the right hand half 30 of which is a vertical transverse section, on the line *b b* of Fig. 1, and the left hand half, a similar section, on the line *c c* of the said figure; and, Fig. 5, an isometrical view, illustrating a structural modification.

35 In the practice of the invention, referring descriptively to the specific embodiment thereof which is herein exemplified, there is provided a fabricated locomotive frame structure, herein illustrated as adapted for 40 application in a locomotive of the "Pacific" or 4-6-0 type. The frame comprises two counterpart side frame members, each having formed integral therewith, a plurality of cross tie sections, said cross tie sections of the 45 two side frame members being disposed between pedestal jaws formed on said members and abutting, at their ends further therefrom, in the middle vertical longitudinal plane of the complete frame. The abutting ends of 50 the cross tie members are rigidly secured together, to constitute a complete fabricated frame or bed structure, by any suitable connecting means, as riveting, welding, or bolts passing through the cross tie sections. The 55 invention also comprehends the association of

other members, hereinafter set forth, with the basic structure above specified.

Referring to the drawing, each of the two counterpart side members of the frame comprises, in an integral part, a top rail, 1, pairs 60 of pedestal jaws, 1^b, depending from the top rail in the usual manner, and intermediate pedestal connections, which, while herein shown in the form of bottom rails, 1^a, of ordinary form, may, if preferred, be upwardly 65 extended above said rail portion. A plurality of cross tie sections, 1^c, is formed integral with each of the side frame members, said cross tie sections being disposed intermediate the pairs of pedestal jaws, that is to say, between a jaw of one pair and the nearer jaw of the next adjacent pair. The cross tie sections are machined on their ends further from the side frame members, and are of such length that, when brought into abutment in, 70 or substantially in, the middle vertical longitudinal plane of the frame structure, the width of said structure shall be that which is desired for the application in the particular design of locomotive in which it is to be applied. The cross tie sections, when so abutted, are secured rigidly together, in the instance exemplified, by bolts, 2, passing through end flanges, 1^d, on the cross tie sections, and nuts, 2^a, but the invention is not limited to such 80 specific connecting means, as the connection may otherwise be effected, as by riveting or welding. The sections may also, if desired, be keyed together, to relieve the bolts of racking 85 strains.

As shown in Figs. 1 to 4 inclusive, the cross tie sections extend for the entire length between the pedestals, and openings, 1^f, are formed in their tops, to reduce their weight. In the structural modification shown in Fig. 90 95 5, they are of materially shorter length, and are entirely clear of the pedestal jaws between which they are interposed, their ends next the side members being integral with the top and bottom rails thereof.

A steam cylinder, 5, associated valve chest, 5^a, and cylinder saddle, 4, are formed integral with each of the side members of the frame, and it will be obvious to those familiar with the construction of locomotives, that supports 100 for valve gears, reversing mechanism, and other elements of the equipment of locomotives, may be similarly associated with the side members.

The interposition of the cross tie members 110

between the pairs of pedestal jaws, as herein described and shown, instead of locating them on the tops of the pairs of jaws, as in Patent No. 1,645,687 aforesaid, presents the 5 advantages of more firmly bracing the side members, in the completed frame structure, and of effecting a better distribution of metal in the integral side members and cross tie sections. The construction is also advantageous, 10 in that the disposition of the cross tie sections, relatively to the pedestals, enables additional transverse members for the support of valve gear parts, etc., to be dispensed with.

The invention claimed as new and desired 15 to be secured by Letters Patent is:

1. In a fabricated locomotive frame structure, the combination of two counterpart side members, each comprising, in an integral part, a top rail, pedestal jaws, depending 20 therefrom, pedestal jaw connections, and cross tie sections, each of which projects laterally from one of the side members and is interposed between one of the jaws of a pedestal and the nearer jaw of the next adjacent 25 pedestal, said cross tie sections abutting against counterpart sections on the other side member; and means by which the abutting sections are rigidly secured together.

2. In a fabricated locomotive frame structure, the combination of two counterpart side members, each comprising, in an integral part, a top rail, pedestal jaws, depending 30 therefrom, pedestal jaw connections, and cross tie sections, each of which projects laterally from one of the side members, and is interposed between one of the jaws of a pedestal and the nearer jaw of the next adjacent pedestal, said cross tie sections having 35 end bolting flanges abutting against counterpart flanges on the other side member; and bolts, passing through the bolting flanges and rigidly securing the abutting sections one 40 to the other.

3. A locomotive frame side member, comprising, in an integral part, a top rail, pedestal jaws, depending therefrom, pedestal jaw connections, and cross tie sections, each 45 projecting laterally from one of the side members, and interposed between one of the

jaws of a pedestal and the nearer jaw of the 50 next adjacent pedestal, said cross tie sections being adapted for abutment against correspondingly located sections on the other side member.

4. A locomotive frame side member, comprising, in an integral part, a top rail, pedestal jaws, depending therefrom, pedestal jaw connections, and cross tie sections, each projecting laterally from one of the side members, and interposed between one of the jaws 60 of a pedestal and the nearer jaw of the next adjacent pedestal, said cross tie sections having end bolting flanges, adapted for abutment against bolting flanges on a correspondingly located cross tie section on the other 65 side member.

5. A locomotive frame side member, comprising, in an integral part, a top rail, pedestal jaws, depending therefrom, and cross tie sections, each projecting laterally from 70 one of the side members, and interposed between one of the jaws of a pedestal and the nearer jaw of the next adjacent pedestal, said cross tie sections being adapted for abutment against the other side frame member. 75

6. A locomotive frame side member, comprising, in an integral part, a top rail, pedestal jaws, depending therefrom, pedestal jaw connections, and cross tie sections, each projecting laterally from one of the side members, and interposed between one of the jaws of a pedestal and the nearer jaw of the next adjacent pedestal, said cross tie sections having end bolting flanges adapted for abutment 80 against bolting flanges on a correspondingly located section of the other side member.

7. A locomotive frame side member, comprising, in an integral part, a top rail, pedestal jaws, depending therefrom, cross tie sections, each projecting laterally from one of the side members, and interposed between one of the jaws of a pedestal and the nearer jaw of the next adjacent pedestal, said cross tie sections being adapted for abutment against the other side member; and a steam cylinder, 90 located forward of the front pedestals of the side member.

ALFRED W. BRUCE.
